UNITED STATES PATENT OFFICE.

JOHN E. BELL, OF NEW YORK, N. Y.

SOOT-BLOWER FOR WATER-TUBE BOILERS.

1,283,048.

Specification of Letters Patent. Patented Oct. 29, 1918.

Application filed March 24, 1917. Serial No. 157,269.

To all whom it may concern:

Be it known that I, JOHN E. BELL, a citizen of the United States, and resident of the city of New York, in the county of 5 Kings and State of New York, have invented certain new and useful Improvements in Soot-Blowers for Water-Tube Boilers, of which the following is a specification.

This invention relates to soot blowers for 10 water-tube boilers; its object being to provide a simple and efficient construction and arrangement of parts whereby the blower pipes are supported in the region of the boiler tubes and yet are effectually protected from the destructive action of the intense heat from the furnace gases.

The invention comprises a metallic structure within and by which a blower pipe is 15 effectually incased and supported, said 20 structure having extended surfaces in contact with the boiler tubes.

The invention also comprises a novel arrangement of the said structure in relation to the baffling and the water tubes.

25 The invention also comprises various features of construction and combinations of parts, which will be hereinafter described and claimed.

In the drawings:

30 Figure 1 is a longitudinal section of a vertical water-tube boiler equipped with soot blower structures embodying the principle of my invention.

Fig. 2 is an enlarged section of a portion 35 of the mud drum and adjacent parts of the water tubes and baffles, showing the sectional blower structure at the bottom of the front baffle adjacent the mud drum.

Fig. 3 is an elevation of two adjoining 40 sections of the said basal blower structure, the cap of one of the sections being removed.

Fig. 4 is an elevation of the detached cap.

Fig. 5 is a plan of Fig. 3.

Fig. 6 is a vertical section, as on the line 45 6—6 of Fig. 3.

Fig. 7 is an elevation of a portion of a baffle showing blower-pipe supporting and protecting sections in conjunction with the adjacent boiler tubes.

50 Fig. 8 is a vertical section through the baffle showing two blower-pipes and their inclined nozzles, together with the supporting and protecting structures therefor, the upper structure being in section and the 55 lower structure in elevation.

Fig. 9 is a horizontal section, as on the line 9—9 of Fig. 7.

Fig. 10 is a section through a modified structure, in a plane longitudinally of the boiler tubes.

60 Fig. 11 is a transverse section, as on the line 11—11 of Fig. 10.

Although I have herein illustrated my invention as applied to a vertical boiler of the Stirling type it is to be understood that 65 the improvements are applicable to other types of vertical water-tube boilers and also to horizontal water-tube boilers.

Referring to the drawings, 12 designates the usual steam-and-water drums of a boiler 70 of the Stirling type; 13 the transverse mud drum; and 14 the banks of tubes which converge from the steam-and-water drums, respectively, to the mud drum and afford intercommunication between the series of 75 drums.

15, 16, 17 designate baffle supported upon the backs of the three banks of tubes respectively. The baffle 15 extends up from the mud drum and terminates short of the 80 front steam-and-water drum, being preferably provided with a rearwardly extending shelf 18 at or near its upper end to direct the gases into the second bank of tubes. The baffle 16 extends from the middle drum 85 along the rear of the middle bank of tubes and terminates short of the lower end of the tubes; and the baffle 17 covers a portion of the rear bank of tubes and holds the gases in the latter as they rise to the up-take 90.

The general arrangement of the baffling and associated parts, excepting as herein-after specifically pointed out, is preferably such as illustrated in my pending application for Letters Patent of the United States 95 filed January 24, 1917, Serial No. 144,188 (being a division of my application Serial No. 35,786, filed June 23, 1915.) In my previous construction the baffling is composed of tiles set in place, and certain of 100 the tiles in the respective baffles are specially constructed to receive and support blower-pipes having jet nozzles extending in the general direction of the draft.

According to my present invention the 105 blower pipes are supported and incased by metal structures having extended surfaces which contact with the boiler tubes. Hence the structures are maintained approximately at the temperature of the tubes, since such 110

heat as the structures absorb is rapidly conducted through the tubes to the water in the interior of the latter. The rise in temperature of the structures thus being limited, the confined blower pipes are effectively protected from the intense heat of the gases flowing through the passes.

- The preferred form of supporting and protecting structure for the blower pipe 20 at the foot of the baffle 15 comprises a series of corresponding sections arranged end to end upon the top of the mud drum; each section being composed of two iron castings, namely a body 21 and a cap member 22. 5 The body is inclined on one side correspondingly with the lower portion of the rear tubes of the first bank, and it is provided with a median longitudinal concave channel 23, shaped to fit snugly against the wall of 10 the adjacent tube. It is also provided at its ends with concavities 24 corresponding in curvature with the boiler tubes, whereby when the series of bodies are assembled the contiguous edges of adjacent bodies closely 15 hug the proximate boiler tubes, as shown. The rearward side of each body is conveniently provided with spaced up-standing webs 25 having projections 26 arranged to bear against the adjacent front tubes of the 20 second bank and thus tend firmly to wedge the body between the two banks of tubes. (See Fig. 2.) These webs terminate at their upper ends below the top of the body and merge with a trough-shaped shelf portion 25 27 extending longitudinally of the body, whereby when the series of bodies are assembled end to end a substantially continuous embracing support for the blower pipe 20 is provided.
- 40 The outer curved portion of the shelf has formed therein a series of spaced recesses 28 for the reception of the downwardly inclined nozzles 29 of the blower pipe, and the body of the casting is provided at its upper edge, 45 in the rear of the shelf, with spaced recesses 30 for the reception of the upwardly inclined nozzles 31. The cap 22 comprises a member having its under portion longitudinally 50 channeled to embrace the upper part of the blower pipe and also having upwardly inclined recesses 32 appropriately formed and positioned to embrace the upper nozzles. The cap has also on its rearward portion 55 downwardly inclined extensions 33 channeled to embrace the tops of the lower nozzles.

When the series of supporting bodies are positioned on the mud drum and the blower pipe with its jet nozzles is imposed on the 60 continuous support thereby provided, the caps are applied to their complementary members; the pipe and its nozzles thus being incased by the sections. The upwardly and forwardly extending nozzles discharge into 65 and among the lower portions of the first

bank of tubes, and the downwardly and rearwardly extending nozzles discharge into and among the lower portions of the second bank of tubes, the steam or air blasts to the respective passes thus being in the general direction of the draft. 70

The preferred form of sectional supporting and protecting structure for the upper blower pipes 20 which are spaced upon the various baffles is illustrated in Figs. 1, 7, 8 75 and 9. Each of these upper structures similarly to the basal structure above described, comprises two complementary members 21, 22, which are so formed and associated as to incase and protect the blower pipe. These 80 sections are snugly and tightly fitted into a transverse slot or opening in the baffle so as to constitute, in effect, a continuation of the latter, the inner surfaces of the sections being concaved, as at 24' so as to present extended contact surfaces to the adjacent tubes, and the inner adjacent portions of the two members being appropriately formed to receive and protect the inclined nozzle of the blower pipe, similarly to the first described 90 construction. Likewise the upper sectional structures are arranged end to end to provide a continuous support and protector for the blower pipe and its nozzles. These structures being appropriately mounted in the 95 respective baffles, the steam or air blasts from the nozzles to the adjacent passes are discharged in the general direction of the draft.

In Figs. 10 and 11 of the drawings, I 100 have shown a modified structure wherein the cap 22 is secured to the body 21 of the section by means, for example, of screws 35, such body having the characteristic extended portions which contact with the boiler tubes. 105 This construction, although applicable to vertical tubes, is more especially adapted to use with horizontal boiler tubes.

It is to be understood that my invention is not limited to the exact details of construction above set forth, as the parts may be variously modified within the principle of my invention and the scope of the appended claims.

I claim—

1. In a water-tube boiler, the combination with a plurality of spaced apart water tubes, of a series of metallic bodies arranged in end to end relation to each other transversely of said tubes, each of said bodies having elongated surfaces extending longitudinally of the tubes and shaped to contact throughout their length with the walls of adjacent tubes and to span the space between said tubes, and a blower pipe 125 extending transversely of the water tubes and supported and incased by said bodies, whereby such heat as the metallic bodies absorb is rapidly conducted through the walls of the tubes to the water in the interior of 130

the latter and the bodies are thus maintained approximately at the temperature of the tubes.

2. In a water tube boiler, the combination with a plurality of spaced apart water tubes and a baffle adjacent thereto, of a series of metallic bodies arranged in end to end relation with each other transversely of the tubes and located within and constituting a part of the baffle, each of said bodies having elongated surfaces extending longitudinally of the tubes and shaped to contact throughout their length with the walls of adjacent tubes and to span the space between said tubes, and a blower pipe extending transversely of the water tubes and supported and incased by said bodies.

3. In a water-tube boiler, the combination with a plurality of water tubes, of a series of metallic bodies arranged in end to end relation with each other transversely of said tubes, each of said bodies comprising a two-part element having elongated surfaces extending longitudinally of the tubes and shaped to contact throughout their length with the walls of adjacent tubes, and a blower pipe extending transversely of the water-tubes and supported and incased by said bodies.

30 4. In a water-tube boiler, the combination with a bank of water-tubes and a baffle adjacent thereto, of a series of metallic bodies arranged in end to end relation to each other transversely of the tubes and located within and constituting a part of the baffle, each of said bodies comprising a two-part element having elongated surfaces extending longitudinally of the tubes and shaped to contact throughout their length with the walls of adjacent tubes and to span the space between said tubes, and a blower pipe supported and incased by said bodies.

35 5. In a vertical water-tube boiler of the type having a mud drum and banks of water tubes converging thereto, a baffle between the banks terminating short of the mud drum, a metal structure located between the baffle and the drum and having extended surfaces in close contact with the adjacent portions of the tubes, said structure comprising a series of body sections having removable caps, and a blower pipe supported and incased by said sections and caps.

6. In a vertical water tube boiler of the type having a mud drum and banks of water tubes converging thereto, a baffle between the banks terminating short of the mud drum, a sectional metal structure located between the baffle and the drum and having extended surfaces in close contact with the adjacent portions of the tubes, and a blower pipe supported and incased by said structure.

65 7. In a vertical water tube boiler of the type having a mud drum and banks of water tubes converging thereto, a baffle between the banks terminating short of the mud drum, a metal structure located between the baffle and the drum and having extended surfaces in close contact with the adjacent portions of the tubes, said structure comprising a series of body sections having removable caps, and a blower pipe supported and incased by said sections and caps.

70 8. In a vertical water tube boiler of the type having a mud drum and banks of water tubes converging thereto, a baffle between the banks terminating short of the mud drum, a metal structure located between the baffle and the drum and having extended surfaces in close contact with the adjacent portions of the tubes, said structure comprising a series of body sections having removable caps, and a blower pipe supported and incased by said sections and caps.

75 9. In a vertical water tube boiler of the type having a mud drum and banks of water tubes converging thereto, a baffle between the banks terminating short of the mud drum, a metal structure located between the baffle and the drum and having extended surfaces in close contact with the adjacent portions of the tubes, said structure comprising a series of body sections having removable caps, and a blower pipe having upwardly and downwardly extended jet nozzles supported and incased by said sections and caps.

Signed at the city of New York in the county and State of New York this 23d day of March A. D. 1917.

JOHN E. BELL.
